SPLIT SIDE BAND AMPLIFIER CIRCUIT

Walter H. Wirkler, Cedar Rapids, Iowa, assignor
to Collins Radio Company, Cedar Rapids, Iowa,
a corporation of Iowa

Application August 4, 1938, Serial No. 223,096

4 Claims. (Cl. 250—17)

My invention relates broadly to an amplification system for double side band waves of the suppressed carrier type, and more particularly to a split side band amplifier for sets of double side band waves in phase quadrature. An amplification system of this type is applicable, for example, in a radio transmission system such as shown in a copending application by John F. Byrne, Serial No. 215,465, filed June 23, 1938, for a Broadcasting system. Another application of the circuit of my invention is for the amplification of single side band waves for use in single side band suppressed carrier transmission systems of the type shown in my copending application Serial No. 176,670, filed November 26, 1937, for Single side band transmitter.

One of the objects of my invention is to provide side band amplification in tubes of one-half the power rating ordinarily required for such purpose.

Another object of my invention is to provide split side band amplification, that is, separate amplification of superior and inferior side bands, in order to produce increased efficiency of amplification.

Still another object of my invention is to provide an amplification system for split side band circuits adapted for single or double side band systems.

A further object of my invention is the provision of means for using the bridge circuit principle in splitting double side band currents into two single side band currents and amplifying each of the single side band currents in a separate amplifier tube.

Another object of my invention is the provision of means for using the bridge circuit principle in combining the single side band currents after amplification to produce the double side band currents required.

A still further object of my invention is to provide a balanced bridge circuit for deriving single side band currents from sets of double side band components in phase quadrature, for transmission exclusive of the other side band component.

Other and further objects of my invention reside in the circuits and arrangements herein disclosed and hereinafter more fully described with reference to the accompanying drawings, in which:

Figure 1 is a block diagram showing the basic arrangement of elements in the split side band amplification system of my invention; Fig. 2 is a schematic diagram of the circuit connections more particularly involved in the split side band

amplifier circuit; and Fig. 3 is a schematic diagram of a modified form of the split side band amplifier, showing the transmission of one only of the side band components.

The block diagram, Fig. 1, shows the modulation and side band amplifier portions of a transmitter embodying my invention of split side band amplification. The source of carrier energy at 1 includes an oscillator and amplifier and the carrier energy is fed on the one hand through phase shifting network 2 to balanced modulator 3, and on the other hand directly to balanced modulator 4, the waves in the different modulators being in phase quadrature. The source of signal modulations, such as a program line at 12, 15 delivers modulation energy to the balanced modulators 3 and 4 through phase shifting networks 5 and 6, respectively, the modulation waves in the different modulators being 90° out of phase. The carrier energy is suppressed in the balanced modulators and double side bands are present in the outputs thereof, 90° out of phase in the separate circuits.

The system of my invention broadly contemplates the division of the side bands in each output into the superior and inferior bands, combining both superior and both inferior components in the separate outputs, and amplifying the single side bands, afterwards recombining superior and inferior side bands to produce double side band waves for radiation, phase relations being adjusted in the amplifier output. The division or splitting of the double side band outputs of the modulators is effected in a bridge circuit 7 adjacent arms of which are constituted by the input circuits of linear amplifiers 8 and 9, each operative on only one side band. The recombining of superior and inferior side bands is effected in another bridge circuit 10, adjacent arms of which feed double side band energy to the radiating system. Phase relations in any particular system may be further adjusted or modified by a phase shifting network 11 in circuit from one of the output arms of the bridge circuit 10.

In the broadcasting system described in the John F. Byrne application, Serial No. 215,465, supra, in combination with other factors, two double side band antenna currents are required, such as are obtainable from the system shown in Fig. 1, and which are of the form:

$i_1 = I_1 \sin \omega t \cos \rho t$; and $i_2 = I_1 \sin \omega t \sin \rho t$; where ω and ρ are carrier and modulation frequency factors, respectively. In the Byrne application these currents are generated directly in the balanced modulator circuits, as would be

the case in Fig. 1 above described in the absence of carrier phase shifting network 2. These currents, representing double side band components, are separately amplified in the Byrne circuit and applied to the antenna system. In the system of my invention, however, the currents are generated in somewhat different form which permits split side band amplification and attendant improved operation. Because of the difference in carrier excitation phase for modulators 3 and 4, Fig. 1, the outputs thereof are, respectively:

$$I_3 = I_1 \cos \omega t \cos \rho t = \frac{I_1}{2} [\cos(\omega - \rho)t + \cos(\omega + \rho)t]$$

$$I_4 = I_1 \sin \omega t \sin \rho t = \frac{I_1}{2} [\cos(\omega - \rho)t - \cos(\omega + \rho)t]$$

The currents I_3 and I_4 are split into two portions in bridge circuit 7, the components in the input to amplifier 8 being added while the components in the input of amplifier 9 are subtracted, thus:

$$\frac{I_3 + I_4}{2} = \frac{I_1}{2} \cos(\omega - \rho)t = I_1 \quad (1)$$

and

$$\frac{I_3 - I_4}{2} = \frac{I_1}{2} \cos(\omega + \rho)t = I_s \quad (2)$$

where I_1 indicates the inferior side band and I_s the superior side band. These two side band components are then amplified separately in amplifiers 8 and 9, respectively, and applied to bridge 10.

Similarly as in the output of bridge 7, the currents in the two output branches of bridge 10 are added in the one branch and subtracted in the other. Using simply I_1 and I_s as above, it being understood that the waves are amplified, however, when recombined, the current in antenna line 15 is

$$i_2 = \frac{I_1 - I_s}{2} = \frac{I_1}{2} [\cos(\omega - \rho)t - \cos(\omega + \rho)t] \\ = I_1 \sin \omega t \sin \rho t$$

And similarly, the current in the other branch 14 at the output of bridge 10 is

$$\frac{I_1 + I_s}{2} = \frac{I_1}{2} [\cos(\omega - \rho)t + \cos(\omega + \rho)t]$$

Phase shifting network 11 shifts the phase of both side band currents by 90°, giving

$$\frac{I_1}{2} [\sin(\omega - \rho)t + \sin(\omega + \rho)t]$$

and the output to the antenna line 14 is therefore $i_1 = I_1 \sin \omega t \cos \rho t$. Thus i_1 and i_2 as supplied to the antenna system are of the form required for radiation in the Byrne broadcasting system.

While a rather complicated network is ordinarily required to shift the phase of a band of frequencies by equal amounts, an ordinary network designed to shift the phase of a single frequency will be entirely adequate for phase shift network 11. The reason for this is the relatively narrow band of frequencies involved. For example: if the carrier frequency is 1000 kilocycles and the highest audio modulation frequency used is 10 kilocycles, the upper side band frequency will be 1010 kilocycles and the lower side band frequency will be 990 kilocycles. In other words, the difference between the highest and lowest frequencies is only a matter of 2%.

The economy of this method of generating the currents i_1 and i_2 is evident from Equations 1 and 2. That is, the maximum amplitude of the

currents I_1 and I_s is only one-half that of the currents i_1 and i_2 . For a constant plate voltage on the side band amplifiers, for example, this means that the two side band amplifiers of this system need have only one-half the peak volt- 5 ampere rating required of side band amplifiers which amplify the currents i_1 and I_2 directly. Further, for a pure tone modulation, linear amplifiers 8 and 9 carry only a single radio frequency current. In the case of 100% modulation by a pure tone, for example, these linear amplifiers would operate at a plate efficiency of approximately 67%. In the case of linear amplifiers carrying double side band current, however, the average power output can be only one- 10 half the peak power output capability of the tube, because the envelope of the radio frequency current wave is in the form of a half sine wave. The result is that the efficiency of such a linear amplifier is only 53% instead of 67% 15 for 100% modulation with a pure tone. The increase in efficiency made possible by the use of this system is not particularly important because in ordinary broadcasting, modulation is with complex tones, and much of the time is considerably less than 100%. The reduction in tube 20 capacity required is quite important, however, especially in the case of high powered radio transmitters; for example, a 500 kilowatt transmitter using the Byrne system of broadcasting 25 and requiring eight tubes for the Byrne circuit, would, by the use of the split side band amplifier circuit of my invention, employ only six tubes, and the proportionate saving in annual tube cost may be seen to be appreciable. 35

Fig. 2 is a schematic diagram of the modulation and split side band amplifier circuits of this invention, in which block 1 indicates the conventional oscillator and amplifier portion of the transmitter. Radio frequency current is supplied to coil L_1 and induces carrier frequency voltage in coil L_2 of phase shift network 2. Condensers C_1 and C_2 and coils L_3 and L_4 complete the phase network which supplies excitation voltage 90 degrees out of phase to the balanced modulators at 3 and 4. In modulator 3, V_1 and V_2 are the tubes of the balanced modulator, A_1 is a filament current source, C_3 , C_{18} and C_{19} are blocking condensers, H_1 is a radio frequency choke, and R_1 is a grid leak resistor. The grids of V_1 and V_2 are connected in parallel, and the plates are connected in push-pull to the tuned output circuit, consisting of condenser C_4 and coil L_5 . No D. C. voltage is applied to the plates of V_1 and V_2 , but these tubes are plate modulated in push-pull by means of audio frequency voltage supplied by the conventional push-pull audio amplifier V_7 , V_8 , through modulation transformer T_2 . T_1 indicates the input transformer to this audio amplifier stage, and A_2 , B_1 and D_1 are the filament, plate and grid current 40 sources, respectively. The double side band output of balanced modulator 3 is induced by coil L_5 into coil L_7 . Modulator 4 is identical with modulator 3, and audio modulating voltage is supplied thereto by an audio amplifier stage V_5 , V_6 , identical with the stage V_7 , V_8 , primed reference characters being employed to indicate similar elements in each. The audio frequency inputs to the two audio amplifier stages are supplied through phase shift networks 5 and 6, from a common program line 12, so that the audio modulating voltages to the two balanced modulators will be essentially 90 electrical degrees out of phase throughout the useful audio frequency range. 45

In the bridge circuit 7, the output of balanced modulator 4 is induced from tuned circuit C₅, L₆, into coil L₉, which is connected to the center tap of coil L₇. The two ends of coil L₇ are connected to coils L₈ and L₁₀, respectively. This connection constitutes a bridge arrangement, such that coil L₈ carries the sum of the two currents, for example, and coil L₁₀ carries their difference. S₁, S₂, S₃ and S₄ are electrostatic shields placed between the coils, as shown, the purpose of which is to enable a high degree of balance to be obtained in the bridge circuits. It is of importance in this application of the bridge principle that the bridge serves not only to combine two currents, but to combine them in such a way that no radio frequency voltage will be induced in coil L₅ as a result of current in coil L₆, nor will there be any induced in coil L₆ as a result of current in coil L₅. This is an essential feature of my invention, inasmuch as any inter-action between the two balanced modulator stages would result in serious cross-modulation and distortion.

The single side band current in coil L₈ induces voltage in coil L₁₁, which is applied to the grid of linear amplifier tube V₉ through blocking condenser C₈. Coil L₁₁ is made selective by condenser C₇, and resistor R₂ is an artificial loading resistor for tuned circuit L₁₁, C₇. The purpose of this additional loading is to prevent the variation in load caused by the periodical flow of grid current in V₉ from seriously upsetting the balance of the bridge circuit. In amplifier 8, C₈ is a blocking condenser, H₄ a radio frequency plate choke, G₁ a source of D. C. plate voltage, H₅ a radio frequency grid choke, D₂ a grid bias source, A₃ a filament current source, and C₉ a neutralizing condenser. Coil L₁₂ and condenser C₁₀ constitute the tuned output circuit for the linear amplifier 8 from which single side band energy is induced into coil L₁₃ of bridge circuit 10. Amplifier 9 includes tube V₁₀ in a linear amplifier stage identical with amplifier 8, and primed reference characters are employed therein to indicate similar elements. Bridge circuit 10 is similar to circuit 7, in that it serves to combine the outputs of the two linear amplifier stages so that they add in the branch connected to phase shift network 11, for example, and subtract in the branch connected directly to antenna circuit 2. Coil L₁₆ is coupled with coil L₁₂' in the output of amplifier 9, and is connected with a center tap on coil L₁₃. The ends of coil L₁₃ are connected respectively with the two antenna circuits to complete the bridge arrangement. Coils L₁₄ and L₁₅, and condenser C₁₁ constitute a 90 degree phase shift network, at 11, which may be designed for the carrier frequency, and yet maintain essentially 90 degree phase shift over the comparatively narrow frequency range required.

In the modified form of my invention shown in Fig. 3, the circuit arrangement is generally similar to the corresponding portion of the single side band transmitter of my copending application Serial No. 176,670, above noted, and not basically different in the preliminary circuit elements from the arrangement shown in Fig. 1 of this application. The carrier oscillator and amplifier 1 and the program line source 12 of modulation energy are the same as in Fig. 1, and the carrier phase shifting network 2 and audio phase shifting networks 5 and 6 effect the same 90° phase displacements characteristic of the same elements in Fig. 1. Amplifiers 20 and 21 are provided in the audio frequency channels and feed modulation energy to the balanced modulators

22 and 23 respectively. The modulators are of the type shown in application Serial No. 176,670, with carrier and modulation energy impressed in push-pull relation on the grids of the tubes, V₁₁ and V₁₂ in modulator 22, and V₁₃ and V₁₄ in modulator 23. Blocking condensers C₁₂ and radio frequency choke coils H₆ are provided in the grid circuits as indicated, and grid bias in the modulators is supplied from sources D₃ and D₄ as shown.

By the application of the bridge circuit of my invention to the combination of the double side band waves in the outputs of both modulators 22 and 23, interaction or cross modulation in the two circuits is prevented. The plate electrodes in the tubes in each balanced modulator are connected together and to the respective load circuit, 24 or 25, thence in common to the source of plate power G₂, through radio frequency choke coils H₇. The load circuits 24 and 25 are inductively coupled to opposite diagonal terminals of bridge circuit 26. Two arms of the bridge are formed by capacities C₁₃ and C₁₄, a third by the load presented by the Class B linear amplifier at 27, and the fourth by a resistor 28 which operates to dissipate the undesired side bands. Amplifier 27 receives the superior or the inferior side bands from both balanced modulators 22 and 23, depending upon whether the outputs of the modulators are subtracted or added in the arm of the bridge comprising the input circuit of the amplifier 27. The bridge circuit 26 is balanced so that no interaction between the balanced modulators 22, 23, can occur. The single side band thus derived and amplified at 27 is fed to 35 the antenna system for radiation.

While I have disclosed my invention in certain preferred embodiments, I do not intend to be limited specifically thereto, and it is to be understood that modifications may be made within the scope of the appended claims.

What I claim as new and desire to secure by Letters Patent of the United States is as follows:

1. In combination with a pair of balanced modulator circuits each delivering double side band currents, means for dividing the double side band currents into inferior and superior side band components, means for separately amplifying the inferior and the superior side band components, means for recombining inferior and superior side band components into a pair of double side band waves of amplified character, and means for shifting the phases of the side band components in one of said double side band waves.

2. A split side band amplifier for dual double side band circuits comprising a bridge circuit supplied at both pairs of opposite terminals with double side band energy from said dual circuits respectively, carrier and modulation factors in said double side band energy at the pairs of opposite terminals being respectively in phase quadrature, adjacent arms of said bridge carrying inferior and superior side band currents due to addition and subtraction respectively of the double side band components therein, separate amplifier means connected with adjacent arms of said bridge for independently amplifying the inferior and superior side band components, and a second bridge circuit supplied at both pairs of opposite terminals with single side band energy from said separate amplifier circuits respectively, adjacent arms of said second bridge 75

circuit carrying double side band energy of amplified character.

3. A split side band system including a bridge circuit, means for supplying said bridge circuit at both pairs of opposite terminals with double side band energy, with carrier and modulation factors respectively in phase quadrature, the double side band energy in adjacent arms of said bridge circuit being additive and subtractive respectively, resulting in the former instance in inferior side band components and in the latter in superior side band components, of like phase; separate amplifier means connected in said adjacent arms of said bridge circuit, a second bridge circuit, and means for supplying said second bridge circuit at the pairs of opposite terminals with said inferior and said superior side band components respectively, the single side band components in adjacent arms of said second bridge circuit being additive and subtractive respectively, resulting in each instance in double side band energy, carrier and modulation factors in the resulting double side band energy in said adjacent arms being respectively in phase quadrature.
4. A split side band system including a bridge

circuit, means for supplying said bridge circuit at both pairs of opposite terminals with double side band energy, with carrier and modulation factors respectively in phase quadrature, the double side band energy in adjacent arms of said bridge circuit being additive and subtractive respectively, resulting in the former instance in inferior side band components and in the latter in superior side band components, of like phase; separate amplifier means connected in said adjacent arms of said bridge circuit, a second bridge circuit, means for supplying said second bridge circuit at the pairs of opposite terminals with said inferior and said superior side band components respectively, the single side band components in adjacent arms of said second bridge circuit being additive and subtractive respectively, resulting in each instance in double side band energy, carrier and modulation factors in the resulting double side band energy in said adjacent arms being respectively in phase quadrature, and means connected with one arm of said second bridge circuit for shifting the phase of the carrier factor in the output thereof.
